ELECTRIC FOOD WARMING STAND

R. Stuart Davis, Jr., Birmingham, Mich., assignor to Valor Enterprises Incorporated, Royal Oak, Mich., a corporation of Michigan

Filed Mar. 1, 1962, Ser. No. 69,032

Term of patent 14 years

(Cl. D81—10)

The rear is substantially the same as the front except for the omission of the switch and switch plate and the addition of a cord outlet.

The electric cord is shown fragmentarily in the several views for convenience of illustration only.

I claim:

The ornamental design for an electric food warming stand, as shown and described.
